METHOD AND APPARATUS FOR IMPROVING THE STRENGTH OF STEEL BARS, ESPECIALLY REINFORCING STEEL

Axel Frøkjaer-Jensen, Charlottenlund, Denmark

Application March 30, 1953, Serial No. 345,443

6 Claims. (Cl. 29—549)

The present invention relates to a method and apparatus for improving the strength of steel bars, especially reinforcing steel, by cold work which comprises twisting or stretching, or both twisting and stretching, and during which the steel bar is held, in the zone of treatment, between two gripping devices, the cold work being thus applied by relative movement of the gripping devices.

According to the known methods of improving the strength of steel bars by cold work, the bars have been fed to the zone of treatment from above or from the side, while after the operation the bars have been removed sideways from the zone of treatment. This involves certain disadvantages, of which will be given further particulars below, and which are especially prevalent in case of long bars, which consequently, according to the methods known, have been cold-worked in pre-cut lengths which, chiefly to facilitate transportation, are rather short, for example under 20 metres.

If the raw material is to be cut into bars of fixed lengths, wastage will occur at the rolling mills and further wastage will likewise occur at the building sites if the lengths required there do not correspond to the lengths of the bars that can be handled in the known machines.

The said disadvantages have been obviated in the present invention according to which the steel bar or bars consist of one or several continuous strings which in the intervals between the cold working periods is or are intermittently conveyed in a longitudinal direction to the zone of treatment for being cold worked there section by section, the bar or bars thereby being conveyed to the zone of treatment through or along the one gripping device and being removed—also in the longitudinal direction—from the zone of treatment through or along the other gripping device.

In this way far greater lengths of reinforcing steel can be handled than by using the known methods because bars up to 100 metres in length, or longer, can be handled. The feeding of the material to the zone of treatment and its removal therefrom require far simpler feed devices than is the case with the plants known, and the feeding can go on at a considerably greater rate than in the latter. The plant consequently consumes less power and has a higher output than known plants of this type.

It will further be seen that the method according to the invention can be applied to the treatment of steel bars consisting of continuous strings which are fed to the zone of treatment section by section for sectional cold-working there.

To ensure treatment of the entire string, its intermittent feeding may, according to the invention, be so arranged that the length of each feed movement of the steel string is shorter than or equal to the length of the zone of treatment, so that no portion of the string can pass the zone of treatment without having been subjected to cold-working.

This, of course, may result in the fact that short portions of the string will be exposed to cold work twice, which, however, is of no consequence, because a portion once cold-worked up to a certain strain is not susceptible to further strain by being again similarly cold-worked.

2

If the steel is fed as a continuous string, it will, according to the method, be appropriate to feed it to the zone of treatment from a storage drum on which the string has been coiled from lengths that have been welded one to another, or from coils as delivered from the rolling mill.

If a twisting operation is included in the treatment, it may be desirable to let the portion of the string which remains on the storage drum participate in the twisting operation, in which case the storage drum may, according to the invention, be supported so as to be rotatable not only on an axis transverse to the feed direction but also on an axis parallel to the feed direction. When the steel string leaves the zone of treatment, it may, according to the invention, be conveyed in such a manner that its front end strikes against a stop, which discontinues the movement of the string, whereupon the steel is cut, with one or more shears, into any predetermined required lengths, so that any needless waste in cutting is avoided. If no special lengths are required at the time of production, the steel may, according to the invention, either be stored in long lengths of, for example, 25—100 metres, or it may be coiled upon a storage drum, from which it may later be uncoiled and cut into required lengths.

Sometimes, in case of treatment comprising twisting operations, it would be desirable to let the take-up drum participate in the twisting movement, for which reason the drum, according to a further elaboration of the invention, can be made rotatable not only on an axis transverse to the direction of the string but also on an axis parallel to it.

Plants working according to the present method can operate continuously, and interruptions will occur only when changing from one storage drum to another.

Even then, however, stoppages can to some extent be avoided by making the steel string continuous, according to a further elaboration of the invention, by welding the end of the string uncoiled from one storage drum to the end of the string from the next storage drum. Such welding must of course be made before the said portion of the string has reached the zone of treatment, but since each treatment takes some time, sufficient time is available for preparing and performing a welding operation. In this way any needless waste in cutting is avoided.

The invention is illustrated below by some instances of the machine, reference being made to the appended drawing.

Fig. 1 shows a plant for subjecting reinforcing steel to cold work according to the invention, as viewed from the side.

Fig. 2 shows a part of another instance of the plant, and

Fig. 3 shows a part of still another instance of the plant. From a drum 3 (Fig. 1) carried by a horizontal axle 2 from a frame 1, and supplied with e. g. 1000 metres raw material, the steel string is passed through a system of straightening rolls 4 to a fixed stock 5 through whose gripping device 6 with adjustable jaws the steel is passed through a number of ring supports, i. e. posts with apertures, only two of which 7, are shown in the drawing, to a pair of feed rolls 8 and thence to a sliding stock 9 having a rotatable grip 10 and then on through a hollow axle 11 to the shears 12 with which the steel is cut off. After the cutting, a pair of feed rolls 13 convey the cold-worked steel bar to adjustable automatic shears 14, 15 and 16, which cut the steel into predetermined desirable lengths whereupon these fall into storage compartments, 17, 18, 19 and 20.

The raw material, which is supplied either in bars or in coils, is welded together and coiled on the drum 3, shown in Fig. 1, in lengths of 1000—3000 metres, dependent on the thickness of the steel; the machine can be made with two drums so that steel is being coiled upon

one drum while the other one is in use for the treatment; when the drum used for the treatment is empty, the free end from the empty drum is welded to the free end of the steel on the drum which has been filled in the meantime, and the production in the machine can continue with the minimum degree of interruption. Prior to the first start, the machine must be threaded, i. e. the steel must be pulled through from the drum 3 to the gripping device 10. When the steel has been inserted in the gripping device 10, the production can commence, and the machine will use the material coiled on the drum 3; when the steel has been welded to the steel on the other drum, the machine is restarted without any adjustment, and the process continues.

When the machine starts, the gripping devices 6 and 10, which are operated by pneumatic or hydraulic pressure, will close around the steel. Then the motor automatically starts and thus, either by a chain drive 21, see Fig. 1, or by a screw drive or by hydraulic presses, moves the stock 9, which at the start is at its innermost position, away from the other stock 5, causing the steel to be stretched; before, after, or simultaneously with the commencement of the stretching operation a motor 22 is started, which, by means of a belt drive 23 and a gear box located in the stock 9, rotates the gripping device 10 so that the steel, which is held by the gripping device 6, is subjected to twisting. When the desired stretching and twisting has been accomplished, the gripping devices 6 and 10 are opened, and the feed rolls 8 are started. The feed rolls 8, which by their rotating movement push the cold-worked steel through the stock 9, at the same time pulling fresh steel from the drum 3 into the machine, are controlled by an adjustable measuring device which stops the feed when the last section of the cold-worked steel reaches the gripping device 10. While the feed rolls 8 are pulling fresh steel into the machine, the stock 9 slides back to its starting position, which is reached immediately after the feed rolls have stopped. When the stock 9 has reached its starting position, the shears 12 cut the cold-worked steel, which is conveyed by the rolls 13 to the shears 14, 15 and 16, which cut it into desired lengths. At the same time, the gripping devices 6 and 10 are closing around the fresh steel, and the next operation can commence.

Fig. 2 shows a storage drum 3, which is rotatable on two axes 24 and 25 at right angles to each other, and Fig. 3 shows a take-up drum 26, which are rotatable on two axes 27 and 28 at right angles to each other.

I claim:

1. A method of producing cold work steel bar material from a coiled length of steel rod stock having a cross-sectional shape substantially the same as that of the bar material to be produced, which consists in feeding a predetermined length of such rod stock from a coil of the same while passing the forward end of such length of rod stock through two clamping chucks located in a predetermined spaced relationship to each other; clamping each chuck into gripping engagement with the stock so fed so as to prevent relative motion between each such chuck and the surface of the stock engaged thereby; then twisting the stock located between such chucks by rotating the chuck last engaged by such stock, about an axis lying parallel to the axis of the stock engaged thereby while holding the other chuck stationary; then, while both chucks are in gripping engagement with such stock, increasing the distance between the chucks to thereby stretch the stock located between them; then releasing the gripping engagement of both such chucks with such stock and advancing the stock extending through such chucks so as to move additional stock from said coil into position with relation to both such chucks; and then repeating said stock twisting and said stock stretching operations.

2. A method of processing rod stock to produce cold work bar material, which consists in feeding a predetermined length of such stock from a coil of the same while

simultaneously subjecting all portions of the length so fed to a straightening operation and while moving the forward end of such length through two clamping chucks located in spaced relationship to each other; clamping each such chuck into gripping engagement with such rod stock so as to prevent relative movement between each such chuck and the surface of the stock engaged thereby; then twisting the stock located between said chucks by rotating one such chuck about an axis lying parallel to the axis of the stock engaged thereby while holding the other such chuck stationary; then while both such chucks are in gripping engagement with such stock, increasing the distance between the chucks to thereby stretch the stock located between them; then releasing the gripping engagement of both such chucks with such stock and advancing the stock so as to move additional stock from said coil into position with relation to both such chucks; and then repeating said stock-twisting and said stock-elongating operations.

3. A procedure such as defined by claim 1 in which each stock-stretching operation is accomplished prior to the stock-twisting of such stock.

4. A procedure such as defined by claim 2 in which each stock-stretching operation is accomplished during each stock-twisting operation.

5. A method of processing rod stock to produce cold work bar material, which consists in feeding a predetermined length of such stock from a coil of the same while simultaneously subjecting all portions of the length so fed to a straightening operation and while moving the forward end of such length through two clamping chucks located in spaced relationship to each other; clamping each such chuck into gripping engagement with such rod stock so as to prevent relative movement between each such chuck and the surface of the stock engaged thereby; then twisting the stock located between said chucks by rotating one such chuck about an axis lying parallel to the axis of the stock engaged thereby while holding the other such chuck stationary; then while both such chucks are in gripping engagement with such stock, increasing the distance between the chucks to thereby stretch the stock located between them; then releasing the gripping engagement of both such chucks with such stock and advancing the stock so as to move additional stock from said coil into position with relation to both such chucks; and then simultaneously severing the twisted and elongated stock to produce bar stock of different lengths.

6. Apparatus for producing cold worked steel bars from a continuous length of rod stock which includes a frame; a coil-supporting spool rotatably mounted on said frame; a rod-straightening device mounted on said frame and adapted to receive rod stock from said spool; a stock-gripping chuck mounted on said frame in alignment with said device; a chuck support mounted on said frame and movable therealong toward and away from said chuck; a second stock-gripping chuck mounted on said support in alignment with said first mentioned chuck; means for rotating said last mentioned chuck and a plurality of aligned shears mounted on said frame in alignment with said chucks for severing rod stock delivered through the chuck mounted on said movable support.
